CLAIM

The ornamental design for a display assembly, as shown and described.

DESCRIPTION

FIG. 1 shows a perspective view of my design for a display assembly according to the invention;

FIG. 2 shows a first side view thereof with the opposite side view being identical;

FIG. 3 shows a second side view thereof with the opposite side view being identical; and,

FIG. 4 shows a top plan view thereof.

The bottom view which is not shown and the broken-line showing of the pallet in FIGS. 1-4, which is for illustration purposes only, form no part of the claimed design.
